2 Sheets-Sheet 2

Fig. 3.

UNITED STATES PATENT OFFICE.

GEORGE H. GILMAN, OF CLAREMONT, NEW HAMPSHIRE, ASSIGNOR TO SULLIVAN MACHINERY COMPANY, A CORPORATION OF MASSACHUSETTS.

PNEUMATIC HAMMER.

Application filed September 30, 1918. Serial No. 256,330.

To all whom it may concern:

Be it known that I, GEORGE H. GILMAN, a citizen of the United States, residing at Claremont, in the county of Sullivan and

5 State of New Hampshire, have invented certain new and useful Improvements in Pneumatic Hammers, of which the following is a full, clear, and exact specification.

This invention relates to pneumatic hammers and more particularly to the pneumatic hammers used in drill sharpeners for operating the upper swaging die, the object of the present invention being to provide means, operably attached to the fluid pressure controlling lever, for holding the valve mechanism in an adjusted position to permit a flow of fluid pressure to one end of the piston to hold the hammer in elevated position, and means for preventing the pressure fluid, 20 which leaks slowly by the moving parts, from accumulating on the opposite end of the piston and so neutralizing the pressure acting on the first end.

In the manufacture of pneumatic hammers, a clearance of about three-thousandths of an inch is allowed between the piston and cylinder, and a clearance of about one and one-half thousandths of an inch between the differential valve and its bushing. During 25 the normal operation of the hammer the piston and valve reciprocate so rapidly that leakage does not occur, or if it does, it is so small as not to materially affect the operation of the hammer. However, when the differential valve is held in an extreme position 30 to permit a flow of pressure fluid to one end of the piston, the leakage past the moving parts accumulates on the other end of the piston and counterbalances the fluid pressure 35 tending to hold the piston to one end of its cylinder, and the piston drops under the action of the force of gravity.

This defect I overcome in my present invention which will be best understood by 40 reference to the following specification and to the accompanying drawings of one illustrative embodiment thereof, while its scope will be more particularly pointed out in the appended claims.

50 In the drawings,—

Fig. 1 is a front elevation of a drill sharpener embodying my invention.

Fig. 2 is a longitudinal sectional view of 55 the pneumatic hammer and its valve chamber.

Fig. 3 is a view similar to Fig. 2, but showing parts in a different position.

Fig. 4 is a transverse section on the line 4—4 of Fig. 3.

Referring to the drawings and to the machine shown therein, while the invention may be embodied in machines and devices other than the specific type herein shown, for the sake of illustration, there is shown one embodiment of the invention in a drill sharpener having a base 2 on which is secured a lower swaging die 3. Bolted to the base at 4 is an upright support 5 for supporting in a vertical position a pneumatic hammer 6 for operating an upper swaging block or die 7. The upper swaging block reciprocates in a vertical guide 8 formed integral with the support 5.

A foot lever 9 is attached to one end of a rocker shaft 10 passing through the base 2, the other end of the rocker shaft carrying a lever 11 for actuating a vertically disposed rod 12 which controls the valve mechanism in a manner to be hereinafter described. A spring 13 is held 80 under compression between a flange on the support 5 and a collar on the valve control rod, to normally hold the rod in an elevated position.

The upper swaging die is reciprocated by a piston rod 14 carried on the lower end of a piston 15, of usual construction, the same comprising a spooled center 16 around which is an annular passage communicating with annular grooves 17 through slots 18. Piston 90 rings may be carried in larger annular grooves 19 near the end of the piston. A beveled projection 20 is carried on the upper end of the piston and is adapted to pass into and have a sliding fit with a recessed valve 95 member 21 carried in the upper end of the cylinder.

This valve member carries a resilient packing and cushioning ring 22 in an annular recess 23, the edge of the packing projecting slightly below the recess so that the beveled edge of the projection 20 will contact with the ring when the piston is in its extreme raised position. A valve 24 having intercommunicating longitudinal and transverse passages, is held seated against a shoulder formed in the member 21, so that it projects slightly into the recess, by a screw plug and coiled spring, as is clearly shown. It will further be noted that the valve is so 110

constructed that the pressure in the upper end of the cylinder is transmitted to the top surface of the valve and accordingly will maintain the same closed, thereby preventing leakage during operation of the motor.

A yoke 25 passes over the valve member and is provided with holes through which pass bolts 26 which are commonly used in hammers of this type to retain a tapered sleeve 27 on the lower end of the hammer. Nuts are threaded onto the ends of the bolts into contact with the yoke and serve to retain the valve member 21 securely in place.

The differential piston valve mechanism and passages leading therefrom, as herein shown, are essentially the same as in the rock drill covered by Letters Patent No. 1,164,496, granted me December 14, 1915, and as that construction is now very common it is thought that an extended description of the parts and their action is not necessary. Pressure fluid is conducted to the inlet opening 28 through a pipe 29, flows alternately to the ends of the cylinder 30 through passages 30, and leaves the cylinder by way of these same passages 30 and exhaust passages 31, leading to the atmosphere at 32. An opening 33 connects the cylinder at its center with the exhaust passages. Annular grooves 34 formed in the cylinder wall are connected by small passages to the ends of the valve chamber and serve to conduct the pressure fluid to one end of the differential valve and exhaust the fluid under pressure from the other end of the differential valve. Stops 35 are fastened in the ends of the valve chamber to limit the motion of the valve.

One of these stops is provided with a stepped bore to receive a valve actuating pin 36 carrying a collar 37 which slides in and has a close fit with the larger bore of the stop. This collar serves as a guide for the pin 36 and also to check fluid pressure leakage because of its close fit in the cylinder and because the beveled head 37 bears against a shoulder on the stop when the pin is forced against it. The pin projects beyond the collar in both directions, the upper end passing through the smaller bore in the stop and contacting with the valve to force it to its extreme raised position, the lower and longer portion of the pin resting in a hole or depression 38 in a lever 39 attached to a rock shaft 40 operated by a lever 39 which is connected to the valve actuating rod 12 by a pin 41.

A valve 42 is provided for closing the exhaust port 32 and cooperates with a housing 40 which consists of two parts 43, 43', the first carrying the valve seat and the second a perforated bridge 44 which acts as a stop or abutment for the valve plunger 45 and as an abutment for the spring 46 which acts on and tends to force the valve to its seat.

The means for operating this valve consists of a bell crank lever 47 pivoted on a bolt 48 fastened to the frame support and connected to the valve actuating rod 12 by a link 49. The coiled spring 13 acting on the valve 42 actuating rod tends to raise the differential piston and close the exhaust valve 42 so that normally the pneumatic hammer is held in a raised position.

When the operator desires to use the swaging mechanism he depresses the foot lever which actuates the valve control mechanism, and so opens the exhaust port 32 and frees the differential valve that the piston and valve can reciprocate and perform their usual function. When the piston travels upward it traps air in the recess and compresses it, thus forming a cushion which absorbs the inertia of the piston and gives the piston a start downward. This cushion of air further serves to keep the piston from contacting with the valve 24 which remains closed during the usual operation of the hammer.

When the operator removes his foot from the lever 9, the control rod 12 is forced upward and so closes the exhaust port and raises the differential valve to permit a flow of fluid pressure to the lower end of the piston. The piston moves rapidly upward and compresses the air trapped in the recess until it contacts with the small valve 24 which it raises, thus exhausting the entrapped air and permitting the piston to seat on the cushion ring 22. If the pressure fluid that leaks by the piston rings and differential valve flows past the projection 20 and the resilient ring 22 it is exhausted to the atmosphere and so cannot accumulate and counterbalance the pressure acting on the lower side of the piston. Valve 42 closes the exhaust port so that, as the air leakage in the different parts goes on, the pressure in the different passages will slowly be built up to the inlet pressure and the leakage will stop. This results in a saving in pressure fluid consumption when the drill sharpener is not in operation. Thus it is seen that I have devised a simple and effective means for normally retaining the upper swaging die in an elevated position and for preventing a loss of pressure fluid when the swaging mechanism is not in operation.

While I have herein shown and described for the purpose of illustration one specific form of the invention, it is to be understood that the same has been chosen for illustrative purposes only and that extensive deviations may be made from the disclosed form thereof without departing from the spirit of the invention.

What I claim is new and desire to secure by Letters Patent is:

1. In a drill sharpener, the combination with a swaging die, a piston for actuating

said die, and fluid distribution means for causing reciprocation of said piston including means for alternately supplying fluid pressure to the opposite sides thereof and for exhausting the fluid including a normally open exhaust means, of means for holding said piston inoperative including means for subjecting it to unequal pressures on opposite sides, and means distinct from 10 said first mentioned exhaust means for preventing equalization of the pressures on the opposite sides of said piston.

2. In a drill sharpener, the combination with a swaging die normally biased toward 15 the work, of controlling means therefor comprising means for raising the die including a cylinder having a piston therein and means for supplying fluid pressure to the space at one end of the piston and exhausting 20 it from the other, and means for holding said piston in raised position including auxiliary exhaust means.

3. In a drill sharpener, a hammer operative to hammer a work piece, fluid pressure 25 means including a cylinder and piston for operating said hammer and including fluid supply and exhaust means operative to establish a pressure at one side of the piston to move the hammer from the work piece 30 and to vent the opposite side of the piston to prevent fluid resistance to such movement, and separate means for exhausting fluid pressure operative when the piston reaches the limit of its travel away from the work 35 piece.

4. In a drill sharpener, a pneumatic hammer including means for supplying and exhausting fluid during the operation thereof, and separate means operative only when 40 said hammer is idle exhausting such part of the fluid pressure therefrom as leaks past the piston when the latter is stationary.

5. In a drill sharpener, a pneumatic hammer, fluid pressure means including a piston 45 for operating said hammer, and means actuated by the piston and closed except when so actuated for exhausting part of the fluid pressure from said fluid pressure means.

6. In a drill sharpener, a pneumatic hammer 50 comprising cylinder and piston elements cooperating to form chambers to which fluid is supplied and from which fluid is exhausted in alternation during operation of said hammer, fluid pressure controlling 55 means including exhaust controlling means for controlling the operation of said hammer, and means independent of said first named means for exhausting fluid from one of said chambers after said exhaust controlling mechanism is closed.

7. In a drill sharpener, a pneumatic hammer having an exhaust passage, fluid pressure means including exhaust controlling 60 mechanism for operating said hammer, and means independent of said first named

means and inoperative during operation of said hammer for exhausting fluid pressure therefrom.

8. In a drill sharpener, a pneumatic hammer, fluid pressure means for operating said 70 pneumatic hammer, and means for exhausting fluid pressure from said hammer, said last named means being inoperative during the operation of said hammer.

9. In a drill sharpener, a cylinder, a piston therein, means including an automatically operated valve for causing said piston to move repeatedly over a limited path in said cylinder during operation of the drill sharpener, and means operative to cause 80 movement of the piston beyond the limits of its normal path at a time when the drill sharpener is not in operation.

10. In a drill sharpener, a piston, means for moving said piston to operate the drill 85 sharpener, cushioning means to limit the upward movement of said piston, and means for rendering said cushioning means inoperative when said drill sharpener is not in 90 operation.

11. In a drill sharpener, the combination comprising swaging means, fluid pressure means including an inlet, and a plurality of outlets communicating with one end of said fluid pressure means for operating said 95 swaging means, certain of said outlets being closed when said swaging means is not in operation.

12. In a drill sharpener, the combination comprising swaging means, fluid pressure 100 means including an inlet, and a plurality of outlets for operating said swaging means, certain of said outlets being closed in all positions of the piston when said swaging means is operative.

13. In a pneumatic hammer, a cylinder, an exhaust passage, a valve to direct pressure fluid to one end of the cylinder, an auxiliary valve controlling said exhaust passage, and means to prevent equalization of 110 pressure in the opposite end of the cylinder when said auxiliary valve is closed.

14. In a pneumatic hammer, a cylinder, a pressure fluid inlet and an outlet, valve means for controlling said inlet and outlet, 115 separate valve means for controlling said outlet, and interconnected means for controlling the valve means.

15. In a pneumatic hammer, a piston, a cylinder, fluid pressure means for forcing 120 said piston toward one end of said cylinder including passages leading to each end of the cylinder, supply and exhaust means, and means for connecting one end of the cylinder to said supply and the other end to said exhaust means, means for closing said exhaust means, and means for preventing fluid pressure accumulations in the end of the cylinder not connected with said supply means.

16. In a pneumatic hammer, a cylinder, a piston therein, means for supplying fluid pressure to one end of the cylinder and exhausting it from the other end, means for closing said exhaust means, and means for preventing fluid pressure accumulations at the end of the cylinder which last communicated with said closed exhaust means before the closure of the latter.
17. In a drill sharpener, an anvil die, a movable die adapted to cooperate therewith and having a normal bias towards said anvil die, means for reciprocating said movable die relative to said stationary die comprising a pneumatic motor, which comprises cylinder and piston members and fluid distributing mechanism including fluid supply and exhaust means, a valve and passage means for alternately supplying and exhausting fluid to cause opposite movements of one of said members relative to the other, and a connection between said movable die and said movable member, means for moving said valve to a position to cause said movable member to retract the movable die from the anvil die, means for closing the exhaust means, and means including auxiliary exhaust means for preventing fluid leakage causing opposite movement of the movable member and die.
18. In a pneumatic hammer, a cylinder, a piston having a normal bias toward one end of the cylinder, a fluid supply connection, distributing ports for the cylinder, a main exhaust connection for the cylinder, a distributing valve, a separate valve for said exhaust connection, and means for maintaining said piston at the end of the cylinder opposite the end first mentioned when said separate exhaust connection controlling valve is closed.
19. In a pneumatic hammer, a cylinder, a piston having a normal bias toward one end of the cylinder, a fluid supply connection, distributing ports for the cylinder, a main exhaust connection for the cylinder, a distributing valve, a separate valve for said exhaust connection, and means for maintaining said piston at the end of the cylinder opposite the end first mentioned when said separate exhaust connection is closed including means for maintaining unequal pressures at opposite ends of the cylinder.
20. In a pneumatic hammer, a cylinder, a piston having a normal bias toward one end of the cylinder, a fluid supply connection, distributing ports for the cylinder, a main exhaust connection for the cylinder, a distributing valve, a separate valve for said exhaust connection, and means for maintaining said piston at the end of the cylinder opposite the end first mentioned when said separate exhaust connection controlling valve is closed including means for main-
- taining a reduced pressure on said last mentioned end.
21. In a pneumatic hammer, a cylinder, a piston having a normal bias toward one end of the cylinder, a fluid supply connection, distributing ports for said cylinder, a main exhaust connection for said cylinder, a distributing valve, a separate valve for said exhaust connection, and means for maintaining said piston inoperative at the end of the cylinder opposite the first mentioned end when said separate exhaust connection controlling valve is closed, said means comprising means for preventing the building up of a fluid pressure in said last mentioned end including a valve automatically opened upon movement of the piston to said inoperative position.
22. In a pneumatic hammer, a cylinder, a piston having a normal bias toward one end of the cylinder, a fluid supply connection, distributing ports for said cylinder, a main exhaust connection for said cylinder, a distributing valve, a separate valve for said exhaust connection, and means for maintaining said piston inoperative at the end of the cylinder opposite the first mentioned end when said separate exhaust connection controlling valve is closed, said means including a valved connection with the atmosphere adapted to be opened by impact of the piston on the valve upon movement to said inoperative position.
23. In a pneumatic hammer, a vertical cylinder, a piston reciprocable therein, common supply and exhaust passages leading to each end of said cylinder, a distributing valve controlling said passages, supply and exhaust connections alternately connectible by said valve to said passages, a stop valve controlling said exhaust connection, means operative to move said distributing valve to connect the upper end of said cylinder to exhaust and the lower end to supply, means for closing said stop valve, and means for preventing equalization of pressures on opposite sides of the piston by leakage after closure of said stop valve.
24. In a pneumatic hammer, a vertical cylinder, a piston reciprocable therein, means including distribution ports for automatically effecting supply of pressure fluid and its exhaust in alternation to the opposite ends of the cylinder, means operative to limit the supply of pressure fluid to the ports leading to the lower end of the cylinder, means operative to prevent discharge from the port leading to the upper end of the cylinder, and means operative to prevent the pressure leaking past the piston from the lower to the upper side thereof from acting on the upper end of the piston.

In testimony whereof I affix my signature.
GEORGE H. GILMAN.
